PROCESS FOR THE SEPARATION OF HYDROCARBONS

John W. Latchum, Jr., Bartlesville, Okla., assignor to Phillips Petroleum Company, a corporation of Delaware

Application November 11, 1943, Serial No. 509,892

5 Claims. (Cl. 260—676)

This invention relates to the separation, purification, and recovery of hydrocarbons. More specifically, the invention relates to a process for the separation of paraffins from unsaturated hydrocarbons in a fluid mixture containing paraffins and olefins having boiling points sufficiently close that separation by conventional fractionation is very difficult if not impossible. The present process is especially suited to the manufacture of a reference fuel comprising chiefly 2,2,4-trimethylpentane suitable for use in knock testing of gasolines.

At the present time, the production of enormous quantities of aviation gasoline has created a demand for abnormally large amounts of reference fuels for use in determining the anti-knock ratings of the gasoline. The branched chain paraffin 2,2,4-trimethylpentane is a standard of reference which has been given a value of 100 on the octane scale for determining the A. S. T. M. knock rating of motor fuels. In the rating of high octane aviation gasoline, tetraethyl lead may be added to the 2,2,4-trimethylpentane. As a substitute for pure 2,2,4-trimethylpentane, specifications have been developed for a reference fuel which comprises a close boiling hydrocarbon fraction having a high concentration of 2,2,4-trimethylpentane. The allowable content of unsaturated hydrocarbons is limited to 0.3 per cent maximum. An important object of this invention is to provide a process by which a close boiling paraffinic hydrocarbon fraction may be produced which fraction contains little, if any, unsaturated hydrocarbons.

Present practice in the manufacture of reference fuel comprising chiefly 2,2,4-trimethylpentane involves the following steps. The base stock is made by polymerization of isobutylene to diisobutylene, and hydrogenating the diisobutylene to isoctane. Alternatively, isobutane may be reacted with isobutylene in an alkylation reaction to yield isoctane. Both of the above reactions are now carried out in large scale operations to produce components for aviation gasoline. The products of these reactions are rather complex mixtures of hydrocarbons from which the desired aviation fuel blending stock is separated by a series of fractionation steps. After fractionation, the aviation gasoline blending stock from a typical aviation gasoline contains roughly 25 per cent of 2,2,4-trimethylpentane. Even after close fractionation of this stock by conventional fractionation the close boiling fraction contains hydrocarbons other than 2,2,4-trimethylpentane as will be apparent from a consideration of a specific case in the following detailed description, and contains also olefins having boiling points in the region of the boiling point of 2,2,4-trimethylpentane. These olefins cannot be removed by conventional fractionation to the extent required for reference fuel. Hydrogenation may be employed

to convert substantially all of the olefin content to saturated hydrocarbons. In carrying out the hydrogenation, a loss in desirable product is sustained due to undesirable reactions which take place during the hydrogenation. The effluent of this hydrogenation step must be fractionated to remove undesirable hydrocarbons formed during the hydrogenation and having boiling points higher or lower than the maximum and minimum allowable in the finished reference fuel. The present invention provides a process by which the unsaturated hydrocarbons may be removed without the disadvantageous results inherent in the hydrogenation procedure.

15 The present invention involves a novel combination of fractionation and treating with sulfuric acid by which a paraffinic fraction comprising substantially pure 2,2,4-trimethylpentane free from unsaturated hydrocarbons may be obtained.

20 By the process of this invention the necessity for refractionation of the treated close boiling fraction, required in the hydrogenation procedure above mentioned, is obviated and little if any loss of desirable paraffins is sustained. A further advantage of the present invention over the hydrogenation procedure resides in the lower costs of construction and operation of equipment for obtaining the desired product. In accordance with the present invention, the charge stock, which may be aviation gasoline blending stock containing 2,2,4-trimethylpentane, is fractionated in fractionators suitable for the separation of a close boiling fraction from said stock. A stream of overhead product comprising 2,2,4-trimethylpentane in concentrated form is contacted with sulfuric acid of such concentration that substantially all of the unsaturated hydrocarbons in the stream are absorbed. The reflux stream to the fractionator consists of the olefin-free effluent from the sulfuric acid treatment. The reflux stream provided in this novel manner aids in the separation of olefins having boiling points close to but higher than the boiling point of 2,2,4-trimethylpentane.

35 It is, of course, old to refine petroleum by treatment with sulfuric acid, but the primary object of such treatment has been to remove asphaltic compounds, sulfur compounds, and to lower the carbon residue, with the accompanying removal of unsaturates occurring as an objectionable side reaction. It is also old to remove the olefins from hydrocarbon mixtures by absorbing the olefins in sulfuric acid, but in this case the primary object has been to obtain the olefins in a state suitable for further reactions, for example, hydrolysis to form alcohols or reaction with aromatics to form alkyl derivatives. Likewise, the purification of a paraffin hydrocarbon by contacting it with concentrated sulfuric acid to remove small quantities of olefins is a known procedure. The present invention involves a new and unobvious use

40

of sulfuric acid treatment of hydrocarbons for removal of olefins in combination with fractionation to obtain new and unexpected results.

Another object of this invention is to provide an improved process for the separation of olefins from paraffins.

Still another object of this invention is to provide an improved process suitable for the manufacture of a close boiling hydrocarbon fraction comprising chiefly 2,2,4-trimethylpentane substantially free from unsaturated hydrocarbons.

Other objects and advantages will be apparent from the following detailed description and the accompanying drawing in which like numerals designate corresponding parts.

Figure 1 is a diagrammatic elevation of apparatus suitable for carrying out the present invention.

Figure 2 is a diagrammatic elevation of a modification of apparatus for carrying out the present invention.

With reference to Fig. 1 of the drawing, the hydrocarbon mixture containing the desired paraffin in admixture with other hydrocarbons is admitted to the system through line 5 to fractionator 6. The fractionator 6 may be of conventional construction and design equipped with a condenser 7, condensate accumulator 8, and suitable means, not shown in the drawing, for supplying heat to the column as is customary. Condensate from accumulator 8 is supplied to the column by line 10 in conventional manner. Uncondensed vapors and condensate may be removed from the run tank or accumulator 8 through lines 11 and 12, respectively. The fractionator 6 serves to remove from the feed stock as overhead the hydrocarbons lower boiling than the desired paraffin thereby determining the initial boiling point of the final product.

Bottom product from fractionator 6 passes via line 14 to the fractionator 16. The fractionator 16 may be of conventional design and provided with suitable means, not shown in the drawing, for supplying heat, as is customary. This fractionator serves to separate hydrocarbons having higher boiling points than the desired paraffin from those boiling in the immediate vicinity of the boiling point of the desired paraffin. The higher boiling hydrocarbons are removed from the base of the fractionating column by line 17. The overhead vapors from the fractionator comprising the desired paraffin in concentrated form, together with other close boiling hydrocarbons not separable therefrom by conventional fractionation, pass via line 18 to the vessel 19. In the vessel 19, the vapors are contacted with concentrated sulfuric acid. Sulfuric acid of 65 to 98 per cent concentration is suitable. Generally, however, acid of 87 to 93 per cent is preferable. The vessel 19 may be provided with bubble plates or packing to insure intimate contact between the acid and the hydrocarbon vapor. The acid is circulated through line 20, withdrawing the acid from a point near the bottom of the vessel and introducing it at the top of the vessel for countercurrent contact with the hydrocarbon vapors. Fresh acid may be added and used acid removed, continuously or batchwise. The sulfuric acid removes the olefins and any other unsaturated hydrocarbons present in the stream of hydrocarbon vapors, by absorption, reaction, or both. Addition compounds formed by reaction with the sulfuric acid remain in the acid phase and tend to accumulate at the bottom of the vessel. The outlet line 21 is provided for removal of the acid and

absorbed hydrocarbons, together with the reaction products formed, for disposal as waste or for further treatment as hereinafter discussed. The treated hydrocarbon vapors, free from unsaturated hydrocarbons, pass through line 23 from which they may be passed through line 24 to the condenser 25 or through line 26 to the vessel 27 as controlled by the valves 28 and 29.

In many cases it is not necessary that the vapors leaving line 24 be further treated. When it is essential that the final product be completely free of sulfuric acid, the vapors are passed to the vessel 27 where they are contacted with a caustic solution in a manner analogous to that employed 10 for acid treatment in vessel 19. From the vessel 27, the vapors may be passed through line 24 to the condenser or through line 30 to the vessel 31 as determined by the valves 32 and 33 which control the flow to these lines. In the vessel 31 15 the vapors are contacted with water to remove any caustic which may be carried in the vapors after treatment in vessel 27. From the vessel 31 the vapors pass to condenser 25. Condensate collects in the run tank or accumulator 35 from 20 which product is withdrawn through line 36. Condensate, consisting of paraffins, free from unsaturated hydrocarbons, is passed through line 37 to the fractionator 16 as reflux.

Two important advantages of the present invention result from the use of olefin-free hydrocarbons as reflux in the fractionator 16. First, it improves the efficiency of the fractionator by reducing the concentration of olefins on the top 25 trays of the fractionator to a value below that which would be present if the fractionating column were refluxed in conventional manner. This reduction in olefin concentration aids in the separation of olefins from paraffins in the fractionator. This permits removal of a higher percentage, particularly of the higher boiling of the olefins, in the bottoms from the fractionator. Second, the lower concentration of olefins in the liquid at the top of the fractionator results in a 30 lower concentration of olefins in the vapor passing overhead from the fractionator. This, in turn, results in a savings in acid requirement in treating the fractionator overhead for removal of olefins.

The acid treatment of the overhead of fractionator 16 removes unsaturated hydrocarbons without conversion of desired paraffins to undesirable hydrocarbons, i. e., hydrocarbons having boiling points higher or lower than the boiling range allowable in the product. Fractionation to meet A. S. T. M. distillation specifications 35 may be completed by the fractionators 6 and 16 and the product removed through line 38 is, therefore, the completed product. In contrast, hydrogenation of a hydrocarbon mixture, even though previously fractionated to meet the distillation specification, produces by undesirable side reactions, such as cracking, hydrocarbons which must be removed by additional fractionation steps. The elimination of the necessity for 40 additional fractionation of the product is an important advantage of the present invention.

With reference to Fig. 2, the hydrocarbon feed stream is fractionated in fractionators 6 and 16 as described with reference to Fig. 1. The overhead vapors from fractionator 16 are passed to the condenser 40; the resulting condensate, collected in the accumulator or run tank 41. Condensate from the run tank 41 flows through line 42 and is admixed with sulfuric acid from line 43 in a centrifugal pump or other suitable mix-

ing device 44. The acid-hydrocarbon mixture is passed to a vessel 45 in which separation of the acid from the treated hydrocarbon liquid takes place. Fresh acid may be added and used acid withdrawn continuously or batchwise. The treated liquid, free from unsaturated hydrocarbons, may be passed through the line 46 to the run tank or accumulator 47. Generally it is desirable that the acid treatment be followed by a caustic wash to remove entrained acid. In this case the treated liquid from the vessel 45 is passed through the line 48, mixed with caustic solution from line 49 in the mixer 50, and introduced into the vessel 51. In the vessel 51 the hydrocarbon stream separates from the caustic solution and may be passed to the run tank 47 or to line 52 for further treatment to remove caustic therefrom. If removal of caustic is desirable, the hydrocarbon stream is mixed with water from line 53 in the mixer 54 and passed to the water separator 55. After separation of the water from the hydrocarbons in vessel 55, the purified hydrocarbon stream is passed to the run tank 47. The product is withdrawn through line 56 while a part of the olefin-free hydrocarbon liquid from the run tank 47 is passed through line 57 to the fractionator 16 as reflux. The advantages of using a paraffinic hydrocarbon liquid reflux free from olefins and other unsaturated hydrocarbons, have been previously cited in the discussion of Fig. 1.

The used acid from the acid treating step may be treated for regeneration of the acid, removal of the olefins, or manufacture of by-products. Such treatment forms no part of the present invention.

For the sake of simplicity, the apparatus has been shown diagrammatically in the accompanying drawing. It is to be understood that control valves, piping, pumps, and other conventional parts of the apparatus described together with auxiliary equipment may be supplied in accordance with the dictates of good engineering practice, without affecting the operativeness of the process as described or departing from the spirit of the invention.

Example I

Aviation gasoline blending stock is produced by polymerization of isobutylene, hydrogenation of the polymer, and fractionation of the hydrogenation effluents. The olefin content of this stock ranges from 0.4% to 1.0% depending upon the operation of the hydrogenation unit and the length of time the catalyst is on stream. With fresh hydrogenation catalyst a product 99.6% hydrogenated is obtained. When the conversion drops to 99.0%, the catalyst is regenerated. This material has a gravity of 68.2° A. P. I. and vapor pressure of 2.5 lbs. per sq. in. at 100° F. The A. S. T. M. distillation is as follows:

Initial boiling point	172
5 per cent evaporated	186
10 per cent evaporated	190
20 per cent evaporated	196
30 per cent evaporated	200
40 per cent evaporated	204
50 per cent evaporated	210
60 per cent evaporated	216
70 per cent evaporated	228
80 per cent evaporated	250
90 per cent evaporated	320
95 per cent evaporated	336
End point	354

This material was fractionated to give a feed stock boiling within the range of about 205° F. to about 215° F. (The boiling point of pure 2,2,4-trimethylpentane is 210.7° F.) The feed stock was then hydrogenated using a nickel hydrogenation catalyst at 700 lbs. per sq. in. at a temperature within the range of about 400 to 600° F. to produce a product containing less than 0.3% unsaturated hydrocarbons. The temperature at the inlet to the catalyst was 400 to 500° F., at the outlet, 370 to 635° F. This product had to be refractionated to produce a product boiling within the range of about 205 to about 215° F. The overall loss by this procedure amounted to 2.5 to 3.0% based on the feed to the last mentioned dehydrogenation step. This loss may be attributed to undesired reactions which take place simultaneously with the hydrogenation, principally the formation of butylenes which in turn are hydrogenated.

Example II

The same starting material used in Example I was processed in accordance with the present invention. The material was fractionated to meet boiling range specifications by the A. S. T. M. distillation test and treated with sulfuric acid for removal of unsaturated hydrocarbons. The acid treatment was carried out at substantially atmospheric pressure. The overall loss by this method amounted to about 1.5% of the hydrocarbon stream passed to the sulfuric acid treatment. The product does not require further fractionation.

Another important advantage of the present invention is shown by the foregoing comparative examples. By the process of the present invention the loss resulting from the olefin removal step is about 1.5% or only slightly in excess of the olefin content of the feed. By the hydrogenation process, the loss ranges from 2.5 to 3%.

I claim:

1. A process for the separation of paraffins comprising chiefly 2,2,4-trimethylpentane from a mixture of hydrocarbons containing 2,2,4-trimethylpentane and olefins comprising fractionally distilling said mixture to produce an overhead stream of hydrocarbons containing 2,2,4-trimethylpentane in concentration together with close boiling olefins, contacting said stream with sulfuric acid of sufficient concentration to remove substantially all olefins from said stream, withdrawing a part of the resulting treated hydrocarbon stream as product, and passing a part of said treated stream of hydrocarbons in liquid phase to the fractional distillation as reflux therefor.

2. The process of claim 1 in which the concentration of sulfuric acid is within the range of 65 to 98%.

3. The process of claim 1 in which the concentration of sulfuric acid is within the range of 87 to 93%.

4. The process of claim 1 wherein said overhead stream is condensed to a liquid and is subsequently contacted with said sulfuric acid as a liquid.

5. A process for the preparation of a normally liquid paraffinic hydrocarbon mixture containing not more than about 0.3 per cent of unsaturated hydrocarbons, which comprises fractionally distilling a normally liquid aliphatic hydrocarbon mixture resulting from polymerization of butylenes and hydrogenation of the resulting polymer to produce a stock having an olefin

content between about 0.4 and 1 per cent to produce an overhead stream of hydrocarbons containing paraffin hydrocarbons in concentration together with a small amount of close-boiling olefins, condensing said overhead stream to a liquid, contacting the liquid so produced with sulfuric acid of sufficient concentration to absorb substantially all olefins from said liquid under conditions such that the liquid hydrocarbon ef-

luent from said contacting contains not more than 0.3 per cent of unsaturated hydrocarbons, withdrawing a part of the resulting treated paraffinic hydrocarbon liquid as a product, and passing a further portion of said treated paraffinic hydrocarbon liquid in liquid phase to said fractional distillation as reflux therefor.

JOHN W. LATCHUM, JR.
